DIFFERENTIAL FEEDING MECHANISM FOR
SEWING MACHINESWalter Myers, Bridgeport, Conn., assignor to The
Singer Manufacturing Company, Elizabeth,
N. J., a corporation of New Jersey

Application October 21, 1933, Serial No. 694,530

18 Claims. (Cl. 112—209)

This invention relates to improvements in work-advancing or feeding mechanisms for sewing machines and has for its object to provide a simple and compact differential feeding mechanism which is particularly adapted for embodiment in a sewing machine work-arm for advancing the work lengthwise of said arm.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

Fig. 1 is a front elevation, partly in section, of a feed-off-arm sewing machine embodying the invention. Fig. 2 is a top plan view of the machine with the head at the free end of the bracket-arm broken away. Fig. 3 is a top plan view of the work-arm, with the cover-plate and throat-plate removed. Fig. 4 represents a vertical section taken lengthwise and substantially centrally of the sewing machine work-arm, and showing in side elevation a portion of the bracket-arm standard and portions of the needle-carrying bar and presser-device. Fig. 5 represents an enlarged transverse section of the feed-bars substantially on the line 5—5 of Fig. 4. Fig. 6 represents an enlarged transverse section of the feed-bars substantially on the line 6—6 of Fig. 4. Fig. 7 represents an enlarged transverse section of the feed-bars substantially on the line 7—7 of Fig. 4. Fig. 8 is a perspective view of the stud-bolt connection between the rock-lever upon the main feed-bar and the link actuated thereby.

The present differential feeding mechanism is herein described and illustrated in the accompanying drawings as embodied in a feed-off-arm sewing machine which is more fully disclosed in my prior U. S. patent application Serial No. 627,409, filed Aug. 4, 1932. Reference may be made to said prior patent application for an understanding of details of construction of the sewing machine not herein disclosed, but it is to be understood that the present invention is not limited in all its aspects to said specific sewing machine.

The sewing machine illustrated in the drawings has a frame comprising a bed including a forwardly extending arm 1 carrying a laterally extending hollow arm 2 which, in turn, carries a rearwardly extending tubular and substantially straight work-arm 3. The arms 1, 2 and 3 are

preferably cast integral and are disposed substantially horizontally coplanar or at the same level, thereby forming a U-bed. The tubular work-arm 3 is open at its top and preferably the entire length thereof, said work-arm being closed by a detachable cover-plate 4, a removable throat-plate 5, and a pair of pivotally secured auxiliary cover-plates 6 disposed at opposite sides of the throat-plate. The throat-plate has a plurality of feed-slots 7 and in the present case a pair of needle-apertures 8. Rising from the frame bed, at the rearward portion of the arm 1, is the standard 9 of a hollow bracket-arm 10 which terminates in a head 11 overhanging the free end of the work-supporting arm 3.

Rotatably journaled in the bracket-arm 10 is a horizontally disposed main shaft 12 extending outside of the bracket-arm at the right hand side thereof, the projecting end of said shaft carrying a clip-belt pulley 13 and a driving-belt pulley 14 with its associated balance-wheel 15. At its opposite end, the main shaft carries a crank-disk 16 operatively connected in any usual or suitable manner, as by means of a link 17, with a vertically reciprocating needle-bar 18. The needle-bar is journaled for endwise reciprocation in suitable bearings provided in the bracket-arm head 11, and in the present instance carries at its lower end a pair of needles 19. Also journaled for vertical movement in the head 11 is the usual presser-bar 20 carrying at its lower end a presser-foot 21.

Disposed within and extending lengthwise of the laterally extending hollow arm 2 of the frame is an actuating shaft 22 journaled adjacent one end in a bearing 23 in said arm 2. The shaft 22 enters and extends transversely across the forward end of the work-arm 3 in a direction substantially normal to the length of the work-arm, said shaft 22 being journaled in a bearing 24 provided in the side wall of the work-arm remote from the carrier-arm 2. The end of the shaft 22 opposite to the work-arm end thereof extends outside of the arm 2 and carries a clip-belt pulley 25 of the same size as the main shaft pulley 13, the two pulleys being connected by a clip-belt 26. Enclosing the belt 26 and the pulleys connected thereby, is a belt-guard 27 disposed externally of the machine frame and detachably secured thereto in any suitable manner, said belt-guard having a removable side cover 28.

Carried by the actuating shaft 22 within the work-arm 3 are the bevel-gears 29 and 30 meshing with bevel-pinions 31 of one half the size of said bevel-gears. The pinions 31 are carried

by horizontally disposed and parallel shaft-sections 32 suitably journaled in the work-arm 3 to extend lengthwise thereof. The shaft-sections 32 have universal joint connections with intermediate shaft-sections 33 connected in like manner with parallel shaft-sections 34 journaled in suitable bearings provided within the work-arm 3 at the free end thereof. At their rearward ends, the shaft-sections 34 carry bevel-gears 35 meshing with bevel-gears 36 (only one pair of gears 35, 36 being shown in the drawings) for driving the vertical-axis loop-takers 37 in which are journaled thread-cases 38. The loop-takers rotate twice for each complete reciprocation of the needles 19 and cooperate therewith in the formation of lock-stitches, but it is to be understood that the present invention is not limited to any specific form of loop-taker mechanism, as it will be evident that it is also adapted, amongst others, for embodiment in a feed-off-arm machine having a chain-stitch looper mechanism, and particularly of the type disclosed in the pending U. S. patent application of A. B. Clayton, Serial No. 692,273, filed Oct. 5, 1933.

The work-advancing feeding mechanism comprises a main feed-dog 39 and an auxiliary feed-dog 40 operating in the feed-slots 7 of the throat-plate 5, the main feed-dog 39 being disposed rearward of the auxiliary feed-dog in the direction of seam formation. The main feed-dog 39 is secured by screws 41 upon the rearward end of a substantially-straight main feed-bar 42 extending lengthwise of the work-arm 3 and fulcrumed to rock and slide upon a pin 43 which is eccentric to its shank portion 44 rotatably adjustable in the fulcrum-block 45 suitably secured upon the bottom wall of the work-arm 3. At its forward end, the feed-bar 42 is formed with a vertical fork 46 embracing a split-block 47 on a feed-advance eccentric 48 which imparts endwise movements to the feed-bar. The eccentric 48 is adjustably secured upon the hub of the bevel-gear 30 in any suitable manner to provide for changing the length of feed of the work.

Secured to the side of the feed-bar 42 by screws 49 is a bar 50 which is formed with a horizontal fork 51 embracing a split block 52 on a feed-lift eccentric 53 secured upon the actuating shaft 22 within the work-arm 3. The eccentric 53 imparts rocking movements to the feed-bar 42 about the fulcrum-pin 43 to thereby raise and lower the main feed-dog 39.

The auxiliary feed-dog 40 is secured by screws 54 upon the rearward end of an auxiliary feed-dog carrier in the form of an auxiliary feed-bar 55 endwise slidably upon the main feed-bar 42 and also extending lengthwise of the work-arm 3. The feed-dog carrying end of the auxiliary feed-bar 55 is reduced in thickness and is guided by an L-shaped angle bracket 56 secured by screws 57 upon a side face of the main feed-bar 42 to overhang the auxiliary feed-bar 55, as illustrated in Fig. 6 of the drawings. A similar L-shaped angle bracket 58 is secured by screws 59 upon the main feed-bar to overhang and guide the forward end of the auxiliary feed-bar 55, which latter is confined against sidewise movement upon the main feed-bar by a retaining plate 60 secured by screws 61 upon the side of the main feed-bar opposite to that upon which the angle bracket 58 is secured, as illustrated in Fig. 7 of the drawings.

Pivotedly secured by a stud-screw 62 upon a side face of the auxiliary feed-bar 55 at a point 75 between the angle brackets 56 and 58 is the rear-

ward end of a link 63 of which the opposite or forward end is apertured to pivotally receive the cylindrical end 64 of a stud-bolt 65 which has an intermediate flattened portion 66 and is reduced and threaded at its opposite end. The flattened portion 66 of the stud-bolt is adjustably fitted into a guideway in the form of a segmental slot 67 provided in a furcation 68 of a bifurcated vertically disposed rock-lever 69, said stud-bolt 65 being secured in adjusted position in the slot 67 by a nut 70 and a washer 71. The other and shorter furcation 72 of the rock-lever is slidably guided by the side of the main feed-bar 42 opposite to that slidably guided by a thickened portion of the furcation 68 below the segmental slot 67. The furcation 72 is pivotally secured upon the main feed-bar 42 by a horizontally disposed stud-screw 73 and a lock-nut 74 to provide for rocking movements of the lever about an axis transverse to the direction of feed. The segmental slot 67 in 20 the furcation 68 is of sufficient length to permit of adjustment of the stud-bolt 65 into horizontal alinement with the pivotal axis of the rock-lever 69, it being understood that the radius of curvature of the segmental slot 67 corresponds to the 25 length of the link 63.

The lower arm of the rock-lever is preferably solid throughout the width thereof and its cylindrically rounded free end 75 is slidably and rockably disposed in a guideway provided by opposed 30 lever-anchoring angle-brackets 76 suitably secured by screws 77 upon the bottom wall of the work-arm 3, whereby said brackets may be relatively adjusted to take up wear.

When the stud-bolt 65 connecting the rock-lever 69 and link 63 is adjusted into horizontal alinement with the stud-screw 73, the main and auxiliary feed-bars are reciprocated in unison. However, when the stud-bolt 65 is adjusted upwardly above the pivotal axis of said rock-lever 40 69, it is evident that the rocking movements imparted to the anchored rock-lever upon endwise reciprocation of the main feed-bar 42 will be transmitted to the auxiliary feed-bar 55, whereby the auxiliary feed-dog 40 will have a greater 45 amplitude of work-advancing movement than the main feed-dog 39.

Outstanding as an advantageous characteristic of the present differential feeding mechanism is the simplicity and sturdy nature of the construction, afforded by the direct connections of the main feed-bar with the actuating shaft within the work-arm, and the described rock-lever and link connections with the auxiliary feed-bar. Furthermore, the present differential feeding 55 mechanism is particularly well adapted for embodiment in a feed-off-arm machine having a work-arm and a carrier-arm for the work-arm arranged coplanar, whereby the feed and loop-taker actuating shaft may be advantageously disposed and driven in the manner herein described.

Having thus set forth the nature of the invention, what I claim herein is:—

1. A feed-off-arm sewing machine having a frame including a bracket-arm, a substantially-straight tubular work-arm extending under said bracket-arm in a direction out of parallelism with a vertical plane containing the longitudinal axis of said bracket-arm, and a carrier for said work-arm, stitch-forming mechanism, differentially movable main and auxiliary feed-dogs, a rotary actuating shaft disposed within said work-arm, means for rotating said shaft in a continuous direction, and connections within said work-arm for imparting differentially timed work-advanc- 75

ing movements to said feed-dogs from said actuating shaft.

2. A feed-off-arm sewing machine having a frame including a bracket-arm, a substantially straight tubular work-arm extending under said bracket-arm in a direction out of parallelism with a vertical plane containing the longitudinal axis of said bracket-arm, and a carrier for said work-arm, stitch-forming mechanism, differentially movable main and auxiliary feed-dogs, a rotary actuating shaft having one end disposed within and extending crosswise of the length of said work-arm, means for rotating said shaft in a continuous direction, and connections within said work-arm for imparting differentially timed work-advancing movements to said feed-dogs from said actuating shaft.

3. A feed-off-arm sewing machine having a frame including a bracket-arm, a substantially straight tubular work-arm having a free end extending under said bracket-arm, and a carrier arm for said work-arm offset laterally from said bracket-arm, stitch-forming mechanism, differentially movable main and auxiliary feed-dogs, a rotary shaft journaled in said carrier arm and extending into one end of said work-arm, said rotary shaft being disposed substantially normal to the length of said work-arm, means for rotating said shaft in a continuous direction, and connections within said work-arm for imparting differentially timed work-advancing movements to said feed-dogs from said actuating shaft.

4. A feed-off-arm sewing machine having a frame including a bracket-arm, a horizontally disposed work-arm having a free end extending under said bracket-arm, and a horizontally disposed work-arm carrier arm substantially coplanar with said work-arm, stitch-forming mechanism, differentially movable main and auxiliary feed-dogs, a rotary shaft journaled in said carrier arm and disposed substantially normal to the length of said work-arm, means for actuating said shaft, and connections within said work-arm for imparting differentially timed work-advancing movements to said feed-dogs from said actuating shaft.

5. A sewing machine comprising a frame having a bed formed with a forwardly extending arm, a laterally extending arm carried by said forwardly extending arm, a rearwardly extending work-supporting arm carried by and substantially coplanar with said laterally extending arm, a bracket-arm rising from the rearward end of said forwardly extending arm and terminating at its free end in a head overhanging the free end of said work-supporting arm, a shaft journaled horizontally in said bracket-arm, a reciprocating needle connected to be driven by said shaft, a second shaft journaled in said laterally extending arm in parallelism with said first mentioned shaft, an operative connection between said shafts, loop-taking mechanism in said work-supporting arm, operative connections for actuating said loop-taking mechanism from said second shaft, and main and auxiliary feed-dog carriers differentially reciprocable within said work-supporting arm, said feed-dog carriers deriving operative movements from said second shaft.

6. A sewing machine having a frame including a bracket-arm, a substantially straight tubular work-arm having a free end extending under said bracket-arm, and a carrier arm for said work-arm offset laterally from said bracket-arm, stitch-forming mechanism, a feed-bar in said

work-arm, a feed-dog carried by said feed-bar, an actuating shaft operatively connected to said feed-bar for imparting work-advancing movements to said feed-dog in a direction lengthwise of said work-arm, said actuating shaft being disposed within and transversely of the length of the work-arm, means for actuating said shaft, an auxiliary feed-dog, and means disposed in said work-arm for imparting work-advancing movements to said auxiliary feed-dog from said feed-bar.

7. A feed-off-arm sewing machine having a frame including a bracket-arm, a substantially straight tubular work-arm having a free end extending under said bracket-arm, and a carrier arm for said work-arm, stitch-forming mechanism, a feed-bar extending lengthwise of said work-arm, a main feed-dog carried by said feed-bar adjacent to the free end of said work-arm, a rotary shaft journaled in said carrier-arm and extending into said work-arm transversely of the length of the work-arm, means for rotating said shaft, an actuating member carried by said shaft within the work-arm and operatively engaging said feed-bar for imparting work-advancing and return movements to said main feed-dog, an actuating member carried by said shaft within the work-arm for raising and lowering the feed-bar, an auxiliary feed-dog disposed adjacent and movable differentially with respect to said main feed-dog, and means disposed in said work-arm for actuating said auxiliary feed-dog from said feed-bar.

8. A feed-off-arm sewing machine having a frame including a bracket-arm, a horizontally disposed substantially straight work-arm having a free end extending under said bracket-arm, and a horizontally disposed work-arm carrier arm substantially coplanar with said work-arm, a main feed-dog carrying bar in said work-arm, a rotary shaft journaled in said carrier arm, means for imparting work-advancing movements to said main feed-bar from said rotary shaft, an auxiliary feed-dog carrying bar slidably disposed upon said main feed-bar, and means operated by said main feed-bar for actuating said auxiliary feed-bar differentially with respect to said main feed-bar in the direction of the length of said work-arm.

9. A feed-off-arm sewing machine having a frame including a bracket-arm, an arm extending forwardly from said bracket-arm, a laterally extending arm carried by the forwardly extending arm, and a rearwardly extending work-arm carried by and substantially coplanar with said laterally extending arm, stitch-forming mechanism, differentially movable main and auxiliary feed-dogs in said work-arm, and means for imparting differential work-advancing movements to said feed-dogs including actuating mechanism supported by said laterally extending arm and operatively connected to said feed-dogs.

10. A sewing machine having a bracket-arm, a tubular work-arm having a suspended free end extending under said bracket-arm, a needle carrying member supported by said bracket-arm, a rotary needle-thread-loop taker journaled within said work-arm, main and auxiliary feed-dogs at the free end of said work-arm, actuating mechanism housed within said tubular work-arm for rotating said loop taker in a continuous direction, and feed-actuating connections housed within said work-arm for imparting differential work-advancing movements to said main and auxiliary feed-dogs.

11. A feed-off-arm sewing machine having a bracket-arm, a substantially-straight tubular work-arm extending under said bracket-arm in a direction out of parallelism with a vertical plane containing the longitudinal axis of said bracket-arm, a carrier arm for said work-arm, a reciprocating needle, mechanism carried by said bracket-arm for reciprocating said needle, a rotary needle-thread-loop taker journaled within said work-arm at the free end thereof, main and auxiliary feed-dogs at the free end of said work-arm, a rotary shaft supported by said carrier arm, means for rotating said shaft, and mechanism operatively connected to said rotary shaft and extending lengthwise of said work-arm for rotating said loop taker in a continuous direction and for imparting differential work-advancing movements to said main and auxiliary feed-dogs. 10
12. Differential feeding mechanism for sewing machines comprising differentially movable main and auxiliary feed-dogs, a feed-bar carrying said main feed-dog, means for actuating said feed-bar to impart operative work-advancing movements to said main feed-dog, an auxiliary feed-dog carrier, and means for imparting work-advancing movements to said auxiliary feed-dog from said feed-bar comprising, a lever pivotally mounted between its ends upon said feed-bar and having oppositely directed arms extending transversely of the direction of feed, anchoring means engaging one arm of said lever to limit the movement of one end of the lever, and a link connecting the other arm of said lever and said auxiliary feed-dog carrier. 20
13. Differential feeding mechanism for sewing machines comprising differentially movable main and auxiliary feed-dogs, a feed-bar carrying said main feed-dog, means for actuating said feed-bar to impart operative work-advancing movements to said main feed-dog, an auxiliary feed-dog carrier, and means for imparting work-advancing movements to said auxiliary feed-dog from said feed-bar comprising, a lever pivotally mounted between its ends upon said feed-bar and having oppositely directed arms extending transversely of the direction of feed, anchoring means engaging one arm of said lever to limit the movement of one end of the lever, and an adjustable connection between the other arm of said lever and the auxiliary feed-dog carrier. 30
14. In a sewing machine having a horizontally disposed tubular work-arm, a feed-bar disposed within and extending lengthwise of said work-arm, a main feed-dog carried by said feed-bar, means for actuating said feed-bar to impart operative work-advancing movements to said feed-dog, an auxiliary feed-dog carrier disposed within said work-arm, and means for imparting work-advancing movements to said auxiliary feed-dog from said feed-bar comprising a vertically disposed two-armed lever pivotally mounted between its ends upon said feed-bar, anchoring means engaging the lower arm of said lever to thereby influence the amplitude of movement of the upper arm of the lever upon reciprocation of said feed-bar, and an adjustable connection between the upper arm of said lever and the auxiliary feed-dog carrier. 40
15. In a sewing machine having a horizontally disposed tubular work-arm, a main feed-bar disposed within and extending lengthwise of said
- work-arm, a main feed-dog carried by said feed-bar, means for actuating said feed-bar to impart operative work-advancing movements to said main feed-dog, an auxiliary feed-dog carrier slidably mounted upon said main feed-bar, a vertically disposed two-armed lever pivotally mounted between its ends upon said main feed-bar, the upper arm of said lever having a segmental guideway intersecting the pivotal axis of the lever, a link having one end secured for adjustment in said guideway and its other end operatively connected to said auxiliary feed-dog carrier, and means operatively anchoring the lower arm of said lever to said work-arm, whereby rocking movements are imparted to said lever upon reciprocation of the main feed-bar lengthwise of the work-arm. 10
16. Differential feeding mechanism for sewing machines comprising differentially movable main and auxiliary feed-dogs, a feed-bar carrying said main feed-dog, means for actuating said feed-bar to impart operative work-advancing movements to said main feed-dog, an auxiliary feed-dog carrier supported by said feed-bar for movement relative thereto, a lever pivotally mounted upon said feed-bar for rocking movements about an axis transverse to the direction of feed, an operative connection between said lever and the auxiliary feed-dog carrier, and fixed lever-anchoring means providing a guideway confining 30 therein one end of said lever, to thereby compel rocking movements of the lever upon actuation of said feed-bar in the direction of feed. 25
17. Differential feeding mechanism for sewing machines comprising differentially movable main and auxiliary feed-dogs, a feed-bar carrying said main feed-dog, means for actuating said feed-bar to impart operative work-advancing movements to said main feed-dog, an auxiliary feed-dog carrier supported by said feed-bar for movement relative thereto, a lever pivotally mounted upon said feed-bar for rocking movements about an axis transverse to the direction of feed, said lever having a rounded end, an operative connection between said lever and the auxiliary feed-dog carrier, and relatively adjustable anchoring brackets confining therebetween said rounded end of the lever for limited rocking and sliding movement. 35
18. In a sewing machine having a horizontally disposed tubular work-arm, a main feed-bar supported in said work-arm for endwise reciprocity and for rocking movements, said feed-bar extending lengthwise of the work-arm, a main feed-dog carried by said feed-bar, means for actuating said feed-bar, an auxiliary feed-dog carrying bar slidably supported by said main feed-bar, a vertically disposed bifurcated lever embracing said main feed-bar and having one of its furcations pivotally secured upon said main feed-bar for rocking movements of said lever about an axis transverse to the direction of feed, the other furcation of said lever having a segmental guideway extending upwardly from the pivotal axis of the lever, a link having one end 50 adjustably secured in said guideway and its other end operatively connected to said auxiliary feed-bar, and anchoring means engaging said lever below the pivotal axis thereof. 55
